UNITED STATES PATENT OFFICE.

RICHARD T. BARTON, OF NEW HAVEN, CONNECTICUT.

IMPROVEMENT IN BRICK-MACHINES.

Specification forming part of Letters Patent No. 137,122, dated March 25, 1873.

To all whom it may concern:

Be it known that I, RICHARD T. BARTON, of New Haven, in the county of New Haven and State of Connecticut, have invented certain new and useful Improvements in Machines for Making Brick; and I do hereby declare that the following is a full, clear, and exact description thereof, whereby a person skilled in the art can make and use the same, reference being had to the accompanying drawing and to the letters of reference marked thereon.

Like letters in the figures indicate the same parts.

My invention consists in certain mechanical means and appliances by which the ground material is pressed into molds and then rotated so as to pass under powerful compressors, by which the brick is forcibly compressed and hardened so that it is delivered from the machine in the best condition for forming a hard and square-edged brick when burned. It also consists in the combination of certain mechanical devices to produce this result.

In the accompanying drawing, on two sheets, Figure 1 is a top view of my improved machine. Fig. 2 is a side view of the same. Fig. 3 is a view, from the right of Figs. 1 and 2, of the end of the machine. Fig. 4 is a bottom view, showing the mechanism which operates the rotating mold-board.

A, &c., are the fixed parts of the frame of the machine. B is the shaft by which motion is communicated to the working parts of the machine. C C¹ C² are cams for raising the levers D D¹ D². They are fixed to the shaft B and turn with it. E E¹ E², Figs. 2 and 3, are springs for bringing the levers D D¹ D² back to their places after the cams have passed so as to allow them to descend. F F¹ F² are plungers moving up and down in fixed slides in the frame of the machine, and are operated by the shorter arms of the levers D D¹ D², respectively. These plungers have at their lower ends the pressing-blocks G G¹ G² for forcing the clay into the molds. H is a rotating mold-board having around near its peripheral edge the molds in which the bricks are formed, as shown at h, &c. I is a steam-pipe, connected with H by a stuffing-box, which allows the latter to turn. It has also the flexible branches

i leading to the pressing-blocks. These pipes are for the purpose of introducing steam to heat the several parts coming in contact with the clay. J is the pug-mill for grinding and pressing the material which forms the brick into the mold h, &c., as they successively pass under it. This mill is of the ordinary construction, and is turned by means of the shaft j. K K' are two cams, which move the top of the rocking lever L alternately backward and forward. M is a reciprocating bar moving in the slides N, which is attached to the lower end of the rocking lever L, and carries at its other end the pawl m for operating the wheel O. This pawl engages one tooth of the wheel O at each movement, and carries the wheel around as M is pushed forward. The wheel O is firmly keyed to the same axis as the rotating mold-board H, and moves it the exact distance between two of the molds h at each movement of the bar M. P is a cam on the shaft B, which, as it revolves, presses down the bar Q and the rear end of the rocking lever R, and raises the stop S. This stop enters one of the holes h in the mold-board at each movement to press upward and out of the mold the brick which has been formed within it. T is a spring for again raising the rear end of the lever R and drawing the stop S downward out of the mold.

The operation of my invention is as follows: The material to form the bricks is placed in the hopper of the mill J. Power is applied to turn the shafts B and j, and steam is admitted through the pipe I. The mold-board H moves round with an intermittent rotary motion, and the molds h, filled with clay or other material, are successively presented under the pressing-blocks G G¹ G². The first block, G, drives the clay down into the mold very compactly, compressing it an inch or more, the bottom of the brick resting firmly upon the frame A. The brick then passes to the next block G¹, and is further compressed, and again to G², when it receives its final compression. Meanwhile new bricks are brought under the first blocks, and are in their turn pressed, as described, the three levers moving simultaneously or in quick succession at each movement of the mold-board. When the brick passes the last lever it comes over the stop S, which lifts it out of

its mold at the same time the previous brick receives its final pressure, and is removed by the attendant.

The stop or lifting mechanism S operates while the mold-board is at rest, and moves down out of the way before it rotates.

The blocks G, &c., are removable, and may be adjusted to different degrees of compression and different thicknesses of bricks by making them of different thicknesses.

Claims.

What I claim as my invention is—

1. The rotating mold-board H, in combina-

tion with the successive pressing devices D F G D¹ F¹ G¹ D² F² G², substantially as herein described.

2. The arrangement of the cams C C¹ C², K K', and P, the levers D D¹ D², L, and R, the bars M m and Q, and the wheel O, and springs E E¹ E² and T, for producing the described motions of the mold-board, the pressing-blocks, and the discharging device, substantially as specified.

R. T. BARTON.
